RAILWAY CAR STRUCTURE

Arthur E. Le Gare, St. Louis, Mo., assignor to
General Steel Castings Corporation, Granite
City, Ill., a corporation of Delaware

Application November 20, 1933, Serial No. 698,841

3 Claims. (Cl. 105—364)

This invention relates to railway vehicles and is particularly adapted for mine cars having stub axles.

In certain types of vehicles, such as those for use in mines and about industrial plants, it is desirable to provide maximum capacity of the car body without exceeding definite limits of height, width and length imposed by clearance conditions along the track over which the car is to operate and also the curvature of the track. One means heretofore suggested for increasing the capacity of such cars is to mount the same upon stub axles projecting laterally from the side walls of the car whereby the floor between the wheels may be lowered beneath the level of the axles.

The main object of the present invention is to improve, strengthen and simplify car structure of the above type by forming the axles integral with the side wall or floor portions of the car.

A more detailed object is to so arrange and shape the integral car wall and axle structure as to provide the maximum strength and capacity with the use of a minimum amount of metal and lower the center of gravity of the car, both light and loaded, so to eliminate as much as possible derailment of the car when rounding sharp curves.

Another detailed object is to enlarge the axle portion of the structure adjacent its connection with the wall forming portion and to utilize the enlargement as a wheel hub bearing and also as an inner end stop for the wheel bearings.

These objects and others are attained substantially by the structures illustrated in the accompanying drawing in which—

Figure 1 is a top view of a portion of a railway mine car.

Figure 2 is a vertical transverse section taken on the line 2—2 of Figure 1.

Figure 2a is a detail on an enlarged scale of parts shown in Figure 2.

Figure 3 is a side view of the structure in Figure 1.

Figure 4 is a vertical longitudinal section taken on the line 4—4 of Figure 1.

Figure 5 is a sectional view corresponding to Figure 2 but showing a modification.

Figure 6 is a side view of the structure shown in Figure 5, the wheel being omitted.

The invention is illustrated as applied to a mine car, the lower portion of the body of which, including the floor, is formed of a continuous seamless metal web. It will be understood, however, that essential features of the invention may

be advantageously applied to other types of vehicles.

The car floor illustrated in Figures 1 to 4 includes vertically offset horizontal portions 1 and 2 connected by upright intermediate webs 3 extending lengthwise of the car. Each upper horizontal portion 2 has an upwardly extending flange 4 to which is secured the car side wall plates 5. Floor portions 2 are upwardly recessed as at 6 to accommodate the upper parts of the wheels 7.

Formed integral with and projecting laterally from the outwardly facing surface of each web 3 is a hollow projection 8 forming a stub axle with a cylindrical outer surface receiving the inner roller bearing race 9. The wheel 7 is mounted upon the stub axle by means of roller bearings 10 confined between inner race 9 and outer races 11. A washer 12 is secured to the end wall 13 of the stub axle by means of a bolt 14 and extends radially beyond the cylindrical surface of the stub axle 8 and forms an outer end stop for the bearing race 9.

Projection 8 is provided adjacent its connection with the web 3 with shoulders 15 and 16, the latter merging with web 3. These shoulders serve to reinforce the connection between the axle and the floor web. Inner shoulder 15 has an outwardly facing surface 17 forming a stop for the bearing race 9. Shoulder 16 has a flat outwardly facing surface 18 forming a bearing or abutment for the inner face of the wheel hub 7a in case of excess play in the roller bearings. The periphery of shoulder 15 cooperates with the grooves 20 formed on a collar in the wheel hub to form an oil and dust seal for the bearings. A housing 22 secured to the outer surface of the wheel hub and a plate 23 seal the bearings 11 from the outside. This housing and plate and also washer 12 may be removed to permit replacement or repair of the bearings and/or the wheel.

The hollow interior of stub axle 8 opens through the inner surface of the body web 3 to facilitate supporting a core in forming the casting. This opening may be closed by means of a plate 21 welded to the web 3, which plate will preferably be flush with the inner surface of the web 3 and form a smooth continuation thereof.

In Figure 5 the cored hollow interior of the stub axle forming projection 24 opens outwardly and its cylindrical wall is thicker than in the previous form to permit attachment thereto of the plate 25 by the annularly disposed bolts 26. The upright intermediate portion 27 of the car floor casting may thus be formed imperforate and the connection between the projection 24 and 55

web 27 is strengthened. The disposition and function of the step shoulders 28 and 29 are the same as in the previous form, as are the structural details of the roller bearing device and 5 wheel shown.

Figure 6 shows the tapped holes 30 in the end of the stub axle 24 for the bolts 26.

By the practice of the invention as illustrated, the construction of the car and, in particular, 10 the connection of the axles thereto is materially strengthened and simplified. As previously suggested, the invention may be applied to other types of cars and the integral axle structure may be formed as a lateral projection on an upright 15 or a sloping portion of the car floor or, where the wheels are located outside the sides of the car, the axle may project from the side wall thereof. It will be understood that the intermediate upright webs 3 in Figures 1 to 4 and the webs 27 in 20 Figures 5 and 6 may be termed as portions of the floor or of the side wall of the car body. Various other details of the embodiments illustrated may be modified without departing from the spirit of the invention and exclusive use of all such modifications as come within the scope of the appended 25 claims is contemplated.

What is claimed is:

1. Vehicle body integral cast metal structure

including a wall part and an outward projection thereon with an outwardly opening hollow interior, the end of said projection being arranged for attachment of a wheel retainer.

2. In a mine car, a cast metal body member including an integral stub axle forming projection with an outwardly opening hollow, a wheel mounting roller bearing unit on said projection, a retainer for said unit applied to the end of said projection, and retainer securing bolts disposed 10 annularly about the hollow in said projection and extending into the wall thereof.

3. In a vehicle, integral cast metal body structure comprising a wall and a stub axle member projecting from the outside thereof, said axle 15 member being closed at its outer end and having a hollow interior opening through the inside of said wall to facilitate supporting a core therein, said wall having a thickened part surrounding said axle member for reinforcing the connection 20 between said wall and member and having a cylindrical outer surface forming an oil and dust seal element and an outwardly facing surface spaced outwardly from the adjacent portion of said wall and forming a wheel hub abutment, and 25 a wheel retainer secured to the closed end of said axle member.

ARTHUR E. LE GARE.
